UNITED STATES PATENT OFFICE.

RICHARD KREMENTZ AND FRIEDRICH KAEELBER, OF NEWARK, NEW JERSEY,
ASSIGNORS TO KREMENTZ & CO., A FIRM COMPOSED OF GEORGE K. KREMENTZ
AND CARL H. LEBKUECHER, OF NEWARK, NEW JERSEY.

TIE-CLASP.

1,152,739.

Specification of Letters Patent.

Patented Sept. 7, 1915.

Application filed January 16, 1915. Serial No. 2,543.

To all whom it may concern:

Be it known that we, RICHARD KREMENTZ and FRIEDRICH KAEELBER, citizens of the United States of America, residing at No. 5 49 Chestnut street, Newark, New Jersey, have invented new and useful Improvements in Tie-Clasps, of which the following is a specification.

The invention relates to tie clasps, and the 10 object is to provide a simple and economical construction free from soldered parts, and in which all unplated surfaces or edges are concealed.

Another object of the invention is to employ a concealed spring for applying tension to the parts of the clasp, the concealment of the spring permitting the employment of an efficient steel spring as distinguished from a spring of softer metal, the 15 latter having been generally used heretofore because of the possibility of giving it a proper finish to correspond with the goods, this being necessary or desirable because springs used for this purpose have been exposed to view.

Another object of the invention is to provide a construction in which certain parts are punched or stamped out instead of being formed by more expensive processes.

30 Other objects of the invention will appear hereinafter.

The invention consists in the features and combination and arrangement of parts hereinafter described, and particularly pointed out by the appended claims.

In the accompanying drawing, Figure 1 is a side elevation of a clasp embodying the invention; Fig. 2 is a longitudinal sectional view of the clasp; Fig. 3 is a view of the 40 two members of the clasp separated from each other and showing a plan view of each part on its inner face; Fig. 4 is a side elevation of the two parts of the clasp separated from each other and with the end of the 45 spring on one part introduced into the other part, this view being intended to show how the two parts may be quickly assembled; and Fig. 5 is a vertical section taken through the pivot ears.

50 In these drawings, the two members 1 and 2 are each formed of an inner part 3 and an outer part 4, each part consisting in itself of a core 4^a of brass or other inexpensive metal having an outer cover or plating

4^b of a more expensive or precious metal as 55 in the form known as rolled gold plate. The outer part 4 is drawn out at its edges to make it thinner, is turned over to present a plated edge, and then this doubled edge is turned in to embrace the raw edge of the 60 inner part. The inner part 3 of member 1 is stamped or struck up with a socket portion 5 having ears 6 and the inner part of 65 clasp member 2 is also struck up with ears 7 with an opening between them at 8. The 70 metal of each inner part 3 adjacent the ears is also raised, as indicated at 9. A coil spring 10 has its helical body portion and one end located in the socket or recess 75 formed by the raised or struck up portion of the inner part 3 of member 1 of the clasp, this spring being confined in this recess by the outer part 4 on one side, by the struck up portion of the inner part 3, and by the ears thereof. The other end of this spring 80 extends from this member 1 under the raised portion of the inner part of the member 2 when the parts are united as in Figs. 1 and 2.

Upon reference to Fig. 3 of the drawing in particular it will be apparent that the 80 ears 6 on the part 3 of member 1, are brought closer together than the ears on the part 3 of member 2, whereby the latter ears will embrace the former ears, and semi-circular pockets will be provided at the sides 85 of the walls of the socket 5 of member 1, which will receive the ears of member 2 in such a snug-fitting manner that the raw edges of the ears will be concealed. To further prevent exposure, these edges of the ears 90 are also turned in at right angles. The walls of the socket 5 on member 1, which extend between the ears 6, are adapted to project into the opening 8 in the struck up portion of the inner part 3 of member 2, so 95 as to insure the concealment of the raw edges of these projecting walls, and further to complete the concealment of the spring whether the jaws of the clasp be open or closed.

100 In assembling the two members of the clasp together it will be noticed, as shown in Fig. 4, that the spring is retained and carried by the member 1, and it is simply necessary to insert the protruding end of 105 this spring under the raised portion of the inner part 3 of the member 2, and by pressing the two members of the clasp together

the pivot openings in the ears will be brought into registration, and then by simply inserting a pivot pin in these registered openings the pivot connection between the two members of the clasp will be made. It will be noticed that the end of the coil spring which is introduced under the raised portion of the inner part or section of member 2 of the clasp will be confined between 5 this portion of the inner part 3 and the outer part 4. The other end of the spring is similarly arranged between the parts of the member 1. This spring, it will be noticed, is entirely concealed, the ears protecting it from view from the sides of the clasp, and the raised portions of the inner members protecting the spring from observation from the ends of the clasp. A steel spring thus may be used which needs no particular 10 finish or plating. The pivot pin is shown as being made of tubular form, gold plated on the inside, and with the gold plating turned over the end of the tube so that when the ends of the tube are upset the 15 base metal will bear against the adjacent faces of the clasp members and thus be completely hidden. It is to be understood however that the pin may be constructed solid. This expedient being obvious, it is not illustrated. Gripping points are provided at 20 11, these being struck up from the inner parts 3 of the pivoted members. It will be noted from the above that a solderless construction is provided; that a concealed 25 spring is employed; that this spring needs no finishing and may be of efficient material such as steel; that all unplated surfaces or edges are concealed including the ends of the pivot pin; and that the construction involves the economical process of punching 30 the pivot ears, the socket for the body portion and one end of the spring on one member, and the socket for receiving the end of the spring in the other member, and also 35 the clasping points.

The walls of the socket 5 embrace the spring coil or body portion sufficiently to retain it in place on the part 1 even when this is separate from the part 2.

50 The pivot pin or tubular form with its end spun or riveted over is indicated at 12.

We claim as our invention:—

1. A tie clasp comprising two members pivotally connected together, each member 55 consisting of an inner and an outer part connected together and a spring hinge connection between them, the spring of which is held between the inner and outer parts of one member and engages between the inner and outer parts of the other member, substantially as described.

60 2. A tie clasp comprising two members, each composed of an inner and an outer

part connected together, each inner part having ears punched out therefrom and with raised portions adjacent said ears, said raised portion on one part forming a socket for receiving a spring, and the raised portion on the inner part of the other member holding the end of said spring, and a pivot 65 pin extending through the ears, substantially as described.

3. In combination in a tie clasp, two members each composed of an inner part and an outer part having its edge turned 70 over the edge of the inner part, ears integral with each inner part with an opening between the ears, each inner part adjacent the ears being raised from its attached outer part, a pivot pin extending through the 75 ears, and a spring engaging between the two parts of each member, substantially as described.

4. A tie clasp comprising two members, each composed of an inner and an outer part 80 connected together, each part having ears punched out therefrom and raised portions adjacent to said ears, the ears of one member being arranged closer together to provide recesses to receive the ears of the other member whereby the raw edges of the ears of both members are concealed, a pivot pin 85 extending through the ears, and a spring having its ends arranged within the spaces afforded between the raised inner and outer 90 parts of the members, substantially as described.

5. A tie clasp comprising two members, each composed of an inner and an outer part 95 connected together, each part having ears punched out therefrom and raised portions adjacent to said ears, the ears of one member being arranged relatively close together to provide recesses for the reception 100 of the ears of the other member, the inner part of the member having the narrowly spaced ears being provided with a socket constituted by the ears and transverse walls extending between the said ears, said walls being adapted to project into the opening 105 provided in the inner part of the other member between its ears, whereby the raw edges of the ears and the socket walls are concealed, a pivot pin extending through the ears, and a spring having its ends arranged within the spaces afforded between the raised inner and the outer parts of the members, substantially as described.

In testimony whereof we have signed our names to this specification in the presence of 110 two subscribing witnesses.

RICHARD KREMENTZ.
FRIEDRICH KAELBER.
